UNITED STATES PATENT OFFICE.

HARRY D. BARTLETT, OF DELAVAN, WISCONSIN.

RADIOLOG.

Application filed August 5, 1926. Serial No. 127,344.

This invention relates to improvements in radio logs.

It is one of the objects of the present invention to provide a handy log for use with radio machines.

A further object of the invention is to provide a radio log which can always be kept in juxtaposition to the radio, or attached thereto, and which will tell at a glance the dial 10 settings of desired stations.

A further object of the invention is to provide a novel form of radio log which is ornamental in appearance.

A further object of the invention is to provide a radio log which is of very simple construction, is inexpensive to manufacture, is easy to manipulate, and is well adapted for the purpose described.

With the above and other objects in view 20 the invention consists of the improved radio log, and its parts and combinations as set forth in the claims and all equivalents thereof.

In the accompanying drawing in which 25 the same reference characters indicate the same parts in all of the views:

Fig. 1 is a plan view of the improved radio log associated with a radio;

Fig. 2 is an enlarged fragmentary view of 30 the log;

Fig. 3 is a view taken on line 3—3 of Fig. 2; and

Fig. 4 is a sectional view taken on line 4—4 of Fig. 3.

35 Referring now more particularly to the drawing it will be seen that the device is formed of an elongated rectangular block or base 6 formed of wood or other suitable material and having its lower surface covered 40 with felt, rubber or other soft material, as indicated by the numeral 7.

The upper surface of the block, except for a strip adjacent the inner edge thereof, receives a metallic frame 8 which is bent over 45 along its forward and side edges to cling to the block. The rear edge of the frame is bent forwardly to provide a flange 9.

Covering the forward and side portions of 50 the frame 8 is a metallic member 10 arranged to provide a slot between it and the portion 8 of the frame for the insertion of indicia strips, as will later be explained.

The upper surface of the block, within the space defined by the frame and member 10, is provided with a plurality of transversely extending, adjacent members 11 forming indicia strip trays.

55 The rear flanged portion 9 of the frame 8 has delineated thereon from end to end and equally spaced apart, numeral designations corresponding to the numerical divisions on the dials of a radio.

Covering the inner or rear portion of the face of the block, and adjacent the frame 8, is a guide member 12 having overturned 60 edge flanges 13 and said guide member is adapted to receive in proper relation wave length tabs 14.

Covering the inner or rear portion of the face of the block, and adjacent the frame 8, is a guide member 12 having overturned 65 edge flanges 13 and said guide member is adapted to receive in proper relation wave length tabs 14.

In use, the device may be conveniently located adjacent a radio 15, as shown in Fig. 1 70 and indicia strips 16, each bearing the name, call letters, location, and wave length of a station, are provided. When a station is located on the radio, the indicia strip therefor is selected and the station is then logged 75 by inserting the strip between the members 8 and 10 and into the tray registering with the numerical designation on the portion 9 which corresponds to the dial reading for the station. After several stations have been 80 thus logged, the wave length tabs 14 which are frictionally held in the member 12 may be adjusted in proper relation, and the dial settings for unfound stations may be readily 85 estimated and the device provides a handy and attractive log for desired stations.

From the foregoing description it will be seen that the improved radio log is of very simple and novel construction, and is well adapted for the purposes set forth.

90 What I claim as my invention is:

1. In combination, an elongated straight base member, an indicia strip holding member thereon, a wave length tab holding member thereon, a plurality of wave length tabs longitudinally removably mounted therein in proper spaced relation, and a plurality of station indicia strips engaged by said first mentioned holding member and movable at right angles to the direction of movement of the wave length tabs, said strip holding member being provided with dial setting graduations and said strips and tabs being in register with predetermined graduations.

2. A radio logging device, comprising an elongated base member, a plurality of adjacent, transversely extending trays mounted on the upper surface of the base member, station indicia strips removably engaged by said trays, a flanged, longitudinally extending guide member mounted on the base mem-

ber inwardly of said trays and at right angles thereto, and wave length tabs mounted in said guide member and movable therein ¹⁰ at right angles to said station indicia strips.

In testimony whereof, I affix my signature.

HARRY D. BARTLETT
